UNITED STATES PATENT OFFICE.

JOSEPH BULOVA, OF NEW YORK, N. Y.

FINGER-RING.

SPECIFICATION forming part of Letters Patent No. 296,312, dated April 8, 1884.

Application filed January 30, 1884. (No model.)

To all whom it may concern:

Be it known that I, JOSEPH BULOVA, of the city of New York, in the county and State of New York, have invented a new and useful Improvement in Finger-Rings, of which the following specification is a full, clear, and exact description.

This invention relates to an improved manner of fastening raised letters or other ornaments upon a finger-ring, stud, or similar article of jewelry.

The invention consists in the combination of a ring having perforated head and stone with an ornament having screw-pins entering said perforations, and with perforated nuts fitting over said screw-pins, all as hereinafter more fully set out.

In the accompanying drawings, Figure 1 is an end view of a finger-ring provided with my improvement. Fig. 2 is a central section on the line x x , Fig. 1; and Fig. 3, a bottom view of the ring.

The letter A represents a finger-ring, a being the shank, and b the head.

25 Into the head b is sunk a stone, c . This stone may have a straight or curved surface, and upon the same is placed a letter or other ornament, d .

To the letter d are rigidly attached two pins, 30 e e , having their lower ends screw-threaded, and extending through holes in stone c and head b up to the inner face of said head. One pin e is situated to the right and one to the left of shank a , as shown in Fig. 3. The 35 holes through which pins e pass are tapering or shouldered, so as to be widest near inner face of head b . In this way they form seats for countersunk nuts f . These nuts have a central perforation to receive the ends of pins

e e , as shown, and two small diametrically-opposite grooves, g g , so that they may be turned by a key. The nuts f are, moreover, concave on their outer face, Fig. 1, to correspond to the concavity of head b .

In order to fasten a letter, d , to a ring, it is 45 placed in position upon stone c , with pins e projecting through the tapering perforations, and the nuts f are screwed upon the ends of pins e . As one pin is placed on either side of shank a , said shank will not interfere with the 50 application of a key to the nuts.

I propose to make my improved fastening of the same proportions for the same class of jewelry, so that one letter, d , may be removed, in case it does not suit, and be replaced by another letter.

By making the nuts f perforated I am enabled to make pins e of sufficient length for properly holding the parts. As the thickness of head b is necessarily limited, this is of considerable importance.

I do not claim to have invented a sleeve-button or other article of jewelry to which an initial is attached by a single pin screwed into the body of the jewelry, as such a construction is shown in Patent No. 157,348, granted to I. Pforzheimer, December 1, 1874; but

I do claim as my invention—

The combination of ring A, having perforated head b and stone c , with the ornament d , 70 having screw-pins e e , and with the perforated nuts f , fitting over pins e , substantially as specified.

J. BULOVA.
